UNITED STATES PATENT OFFICE.

OLLIE J. BERGER, OF CHICAGO, ILLINOIS, ASSIGNOR TO CHICAGO FORGING & MANUFACTURING COMPANY, OF CHICAGO, ILLINOIS, A CORPORATION OF ILLINOIS.

HINGE.

Application filed February 8, 1926. Serial No. 86,716.

My invention relates to a hinge and particularly to a hinge for relatively heavy doors in which a maximum of stability is desired, combined with ease of rotation.

5 Other objects of my invention will appear from time to time in the course of the specification and claim.

I illustrate my invention more or less diagrammatically in the accompanying drawings, wherein—

Fig. 1 is a front view.

Fig. 2 is a section on the line 2—2 of Fig. 1.

15 Fig. 3 is a section on the line 3—3 of Fig. 2.

Like parts are indicated by like symbols throughout the specification and drawings.

A indicates a generally flat plate or support provided on its bottom with an outwardly projecting flange A¹. The plate is 20 penetrated by a plurality of screw apertures A² having the bevelled walls A³.

Aligned along the central portion of the plate are a plurality of lugs B perforated as 25 at B¹ to receive the pivot pin B². Each such lug is provided with a generally squared face B³ converging upon the flattened top B⁴ to form a relatively sharp corner B⁵. The opposite side of the lug may be rounded 30 or tapered as at B⁶.

C generally indicates the hinge member proper having the branches C¹ and C² perforated with screw apertures C³. The inner end C⁴ of the hinge is rounded or inwardly inclined as at C⁵ and terminates in a plurality of tongue portions C⁶, the intermediate ones adapted to penetrate between the lugs B and the outer ones adapted to engage the outer faces of the terminal lugs of the series. 40 Each tongue C⁶ is rounded at its outer end,

as at C⁷, to conform generally to the surfaces B⁶ of the lugs. The tongues and the lugs are so proportioned that when the hinge is swung into the closed position of Fig. 2 the intermediate edges C⁸, of the hinge member, 45 abut against the corners B⁵ of the lugs, limiting the inward movement of the hinge, and providing a close joint.

The hinge may be inwardly reinforced, for example, by the veins D extending to the 50 rims D¹ surrounding some of the apertures C³.

It will be realized that whereas I have illustrated a practical and operative device nevertheless many changes might be made 55 in the size, shape, number and disposition of parts without departing from the spirit of my invention as expressed in the claim hereof.

I claim:

60 In a hinge, a base plate, a plurality of abutment lugs upwardly projecting from the face thereof, a hinge body, the pivot end of which is slotted to penetrate between said abutments, the interpenetrating tongues and 65 the abutments being apertured in line, the abutments being squared on their forward faces and rounded on their rear faces, the outer ends of the hinged tongues being 70 formed to conform to the round portions of the abutments, the opposed parts being so shaped and proportioned that the portions of the hinge body between the tongues closely engage the squared corners of the abutments 75 when the hinge is in closed position.

Signed at Chicago, county of Cook, and State of Illinois, this 25th day of January, 1926.

OLLIE J. BERGER.
